[57] **CLAIM**

The ornamental design for a flower pot cover, as shown and described.

DESCRIPTION

FIG. 1 is a perspective view of our new flower pot cover design;

FIG. 2 is a side elevational view thereof;
FIG. 3 is a top plan view thereof;
FIG. 4 is a bottom plan view thereof;
FIG. 5 is a perspective view of a second embodiment of our new flower pot cover design;
FIG. 6 is a side elevational view thereof;
FIG. 7 is a top plan view thereof;
FIG. 8 is a bottom plan view thereof;
FIG. 9 is a perspective view of a third embodiment of our new flower pot cover design;
FIG. 10 is a side elevational view thereof;
FIG. 11 is a top plan view thereof;
FIG. 12 is a bottom plan view thereof;
FIG. 13 is a perspective view of a fourth embodiment of our new flower pot cover design;
FIG. 14 is a side elevational view thereof;
FIG. 15 is a top plan view thereof;
FIG. 16 is a bottom plan view thereof;
FIG. 17 is a perspective view of a fifth embodiment of our new flower pot cover design;
FIG. 18 is a side elevational view thereof;
FIG. 19 is a top plan view thereof;
FIG. 20 is a bottom plan view thereof;
FIG. 21 is a perspective view of a sixth embodiment of our new flower pot cover design;
FIG. 22 is a side elevational view thereof;
FIG. 23 is a top plan view thereof;
FIG. 24 is a bottom plan view thereof;
FIG. 25 is a perspective view of a seventh embodiment of our new flower pot cover design;
FIG. 26 is a side elevational view thereof;

FIG. 27 is a top plan view thereof;
FIG. 28 is a bottom plan view thereof;
FIG. 29 is a perspective view of a eighth embodiment of our new flower pot cover design;
FIG. 30 is a side elevational view thereof;
FIG. 31 is a top plan view thereof;
FIG. 32 is a bottom plan view thereof;
FIG. 33 is a perspective view of a ninth embodiment of our new flower pot cover design;
FIG. 34 is a side elevational view thereof;
FIG. 35 is a top plan view thereof;
FIG. 36 is a bottom plan view thereof;
FIG. 37 is a perspective view of a tenth embodiment of our new flower pot cover design;
FIG. 38 is a side elevational view thereof;
FIG. 39 is a top plan view thereof;
FIG. 40 is a bottom plan view thereof;
FIG. 41 is a perspective view of an eleventh embodiment of our new flower pot cover design;
FIG. 42 is a side elevational view thereof;
FIG. 43 is a top plan view thereof;
FIG. 44 is a bottom plan view thereof;
FIG. 45 is a perspective view of a twelfth embodiment of our new flower pot cover design;
FIG. 46 is a side elevational view thereof;
FIG. 47 is a top plan view thereof; and,
FIG. 48 is a bottom plan view thereof.
The flower pot cover has no substantial thickness.
